TOWEL CABINET

Leo M. Harvey, Los Angeles, Calif.

Application October 5, 1934, Serial No. 746,983

20 Claims. (Cl. 164—84.5)

This invention relates to a dispensing device and relates more particularly to a towel cabinet for supplying or dispensing toweling. A general object of this invention is to provide a simple, practical and improved towel cabinet for dispensing paper toweling.

This application relates to towel dispensing devices of the general character described and claimed in my co-pending application Serial No. 10 746,984, filed October 5, 1934, and Letters Patent of the United States Number 2,067,760, granted to me January 12, 1937.

The common forms of towel cabinets in general use embody towel dispensing or delivering mechanisms that may be repeatedly operated without appreciable manipulation or delay. The users of the cabinets often repeatedly actuate them to withdraw quantities of towels or toweling greatly in excess of their needs or requirements. 15 This needless and wasteful withdrawal of toweling is costly and rapidly depletes the supplies of toweling in the cabinets. The towel cabinets now in use usually embody levers, buttons or other devices that must be engaged and manipulated to deliver or allow the withdrawal of towels or toweling. These levers, buttons, etc., are engaged by the wet hands of the users and soon become soiled, unsightly and unsanitary.

Another object of the invention is to provide 20 an effective towel cabinet that requires a series of manual acts or manipulations for its complete actuation and for conditioning it for further actuation, said required manipulations being such that they usually deter the user from repeatedly operating the cabinet.

Another object of the invention is to provide a 25 towel cabinet embodying a means controlling the withdrawal of toweling that may be released and actuated through the medium of a portion of clean toweling accessible for engagement through an opening in the case, said portion of toweling being received by the user who engages it. The towel cabinet of the present invention may be 30 easily and conveniently operated to permit the withdrawal of a length of toweling without engaging buttons, levers or like unsanitary operating devices.

Another object of the invention is to provide a 35 towel cabinet in which the delivered or projected portion of toweling must be torn or cut free by the user, when he operates or manipulates the device in the usual or intended manner, before the control means can be released and reactivated to permit the withdrawal of more toweling, and 40 this requirement usually deters the user from

needlessly actuating the cabinet to receive excessive amounts of toweling.

Another object of the invention is to provide 45 a towel cabinet that involves a control governing the withdrawal of toweling from the cabinet, said control including a rotatable member in the cabinet or case engaging the toweling to prevent its withdrawal when held against rotation and means for holding the member against rotation releasable by pressing a portion of exposed toweling 50 against the member in a manner to turn it. The actuation or release of the control member does not require that the user directly engage or manipulate any mechanical part of the device.

Another object of the invention is to provide 55 a towel cabinet of the character mentioned in which the rotatable control member governing the withdrawal of the toweling has supporting and feeding engagement with the supply roll of toweling so that a shaft or spindle for supporting 60 the supply roll is not required.

Another object of the invention is to provide 65 a towel cabinet that is attractive and slightly in appearance and does not normally carry a protruding piece of toweling and does not include 70 projecting operating levers, buttons or the like.

A further object of the invention is to provide 75 a towel cabinet characterized by a simple inexpensive case whose interior is made conveniently accessible for the insertion of the supply roll of 80 toweling by swinging open its outer section.

The various objects and features of my invention will be fully understood from the following 85 detailed description of a typical preferred form and application of the invention, throughout 90 which description reference may be made to the accompanying drawings, in which:

Fig. 1 is a front elevation of the towel cabinet provided by the invention. Fig. 2 is a side elevation of the towel cabinet. Fig. 3 is an enlarged 95 vertical detailed sectional view of the lower portion of the device, being a view taken as indicated by line 3—3 on Fig. 1 and illustrating the members of the control in their normal positions. Fig. 4 is an enlarged fragmentary vertical detailed 100 sectional view taken substantially as indicated by line 4—4 on Fig. 3. Fig. 5 is a fragmentary vertical detailed sectional view taken substantially as indicated by line 5—5 on Fig. 4. Fig. 6 is a 105 view similar to Fig. 5 illustrating a different position of the control mechanism parts. Fig. 7 is a fragmentary vertical detailed sectional view taken substantially as indicated by line 7—7 on Fig. 6. Fig. 8 is an enlarged fragmentary vertical 110 sectional view taken substantially as indicated by 115 line 8—8 on Fig. 7.

line 8—8 on Fig. 3 and Fig. 9 is a fragmentary vertical detailed sectional view similar to Figs. 5 and 6 illustrating another position of the mechanism parts.

- 5 The towel cabinet provided by this invention includes, generally, a cabinet or case 10 for containing a supply roll 11 of toweling, and a control for governing the withdrawal of the toweling from the case 10, said control including a member 12 over which the toweling T must be moved to be withdrawn from the case 10, releasable means 13 limiting movement of the member 12 to limit the amount of toweling T that may be withdrawn from the case at one operation and means 14 independent of the means 13 which may prevent the withdrawal of further toweling until the withdrawn portion of toweling is cut free.
- 10
- 15

The particular cabinet or case 10 shown in the drawings is adapted to be attached to or mounted on a wall or vertical support, it being understood that the cabinet may be designed for arrangement on legs or other supports. The case 10 is a hollow structure for containing the supply roll 11 of toweling and for housing the control mechanism. It is a feature of the invention that the case 10 is a simple inexpensive structure comprising two sections A and B. The sections A and B may be formed of sheet metal, or the like, and are hingedly or pivotally connected for relative movement. The section A comprises the back wall 15 of the case and the bottom 16. The back wall 15 is adapted to be suitably secured to a wall or vertical support and the bottom 16 projects horizontally forward from the back wall. The section B comprises the top 17, the spaced ends or sides 18 and the front 19 of the case. The sides 18 are adapted to join or engage the back wall 15 and the bottom 16 when the section B is in its normal or closed position. The top 17 may be substantially horizontal and may overlap the upper end of the back wall 15.

While the front 19 of the case may be a plain front wall it is preferred to make it in the shape or configuration illustrated throughout the drawings. The front 19 illustrated in the drawings has an upper portion 20 that is convex or rounded outwardly and downwardly from the top 17 and then downwardly and inwardly to join an intermediate portion 21. The portion 21 is also bowed or rounded outwardly and forwardly and then downwardly and inwardly where it joins a lower convexed or rounded portion 22. The upper convex portion 20 may be curved about a center or axis spaced substantially midway between the back wall 15 and its outermost surface portion. The rounded or convexed portions 20, 21 and 22 are graduated in diameter, the portion 20 being of the largest diameter and extent and the portion 22 being of the smallest diameter and extent. The surfaces of the portions 20, 21 and 22 preferably extend forwardly to a common vertical tangential plane. The front 19 shaped as just described is attractive and is of particular utility as will become evident from the following description of the control mechanism.

In accordance with the invention the case section B is hinged or pivoted to the section A so that it may be swung forwardly and downwardly to permit the insertion of the supply roll 11 in the case. Pivot pins 23 are carried by suitable brackets 24 on the bottom 16 and extend through openings in the sides 18 to pivotally connect the section B with the section A. The common axis

of the pivotal connections between the sections A and B is preferably spaced substantially midway between the front and rear extremities of the bottom 16. A suitable lock or latch 25 may be provided to connect the top 17 with the back wall 15 to hold the section B in its normal closed position. Means is provided on the case section A to guide and aid in supporting the supply roll 11 of toweling. Vertically disposed plates 26 project upwardly from the bottom 16 and are spaced from the sides 18. The plates 26 are inwardly offset adjacent their upper ends to have guide parts 27 which are adjacent the opposite ends of the roll of paper toweling 11 to maintain the roll in its proper position. A support 28 extends between and is connected to the plates 26. The support 28 is inclined downwardly and forwardly and may aid in supporting the supply roll 11 when the roll becomes reduced in diameter. It is to be understood that the roll 11 is primarily supported by the member 12 as will be hereinafter described. The large outwardly bowed or curved portion 20 of the front 19 forms a socket or pocket which receives the forward portion of the supply roll 11.

The control is an important feature of the invention and operates to govern the removal or withdrawal of the toweling T from the case 10. The control is housed entirely within the case 10 and may be released and actuated by the user without engaging any mechanical part of the device. The control includes the member 12 which is the principal element of the control mechanism. The member 12 operates to support and feed the supply roll 11 and constitutes a backing or support for a portion of toweling T that may be engaged or acted on by the user to release and actuate the control.

The member 12 is in the nature of a roller or roll positioned below the supply roll 11 and rotatable about a horizontal axis. The roll or member 12 is positioned in the case 10 so that its forward portion is received in the pocket formed by the front portion 21. Axles or trunnions 29 are provided on the opposite ends of the member 12 and are rotatably received in openings in the plates 26 to support the member for rotation. The member 12 is spaced above the bottom 16 and carries or supports the supply roll 11. The supply roll 11 rests on the member 12 as illustrated in Figs. 3, 5, and 6 of the drawings, and is held in cooperation therewith by gravity. The rolling contact of the periphery of the member 12 with the supply roll 11 tends to feed or rotate the supply roll 11 when the member is turned in the direction indicated by the arrow X. The toweling T is trained forwardly from the lower peripheral portion of the supply roll 11 and downwardly over the forward peripheral face of the member 12. From the member 12 the toweling T passes downwardly and rearwardly to be withdrawn through an opening 30 in the bottom 16. The member 12 may be formed of wood or the like and is preferably provided with a peripheral covering of rubber or similar material for cooperating with the toweling T.

A spring urged roller 31 is rotatably supported in the lower forward corner of the case 10 to hold the toweling T against the periphery of the member 12. The roller 31 is partially received in the pocket formed by the portion 22 of the case front 19. Trunnions 32 on the opposite ends of the roller 31 are rotatable and shiftable in slots or elongated openings 33 in the plates 26. 75

Springs 34 are connected with the trunnions 32 to urge the roller 31 toward the member 12 whereby the toweling passing between the roller and member is suitably gripped or engaged. The end portions of the roller 31 may be of reduced diameter so that the roller has limited engagement with the central portion of the strip of toweling T. Means is provided at the opening 30 whereby the user may conveniently cut the withdrawn portion of toweling T free from the main portion of toweling within the case. The forward wall or edge of the opening 30 is shaped to form a cutter against which the toweling T may be drawn. In the particular form of the invention illustrated in the drawings sharpened serrations or teeth 35 are provided at the forward edge of the opening 30 to effectively cut the toweling T.

It is a feature of the invention that an opening 36 is provided in the wall of the case 10 whereby the user may engage and act on the toweling T trained over the forward portion of the member 12 to move the member to release the means 13 and initiate the downward delivery or discharge of the toweling through the opening 30. The opening 36 is provided in the rounded or curved portion 21 of the case front 19 and is preferably equally spaced between the sides 18 so that the middle portion of the strip of toweling is exposed for engagement. The opening 36 may be substantially rectangular and of substantial vertical length so that the user may conveniently press on the exposed toweling to turn the member 12 as required. The user of the device in engaging the toweling T through the opening 36, to release the means 13 and initiate the delivery of the toweling, does not engage any part of the apparatus and only engages a clean portion of toweling which he later withdraws for his use.

The means 13 normally holds the member 12 against rotation to prevent the withdrawal of the toweling T and is releasable by turning the member 12 in a reverse direction. The principal function of the means 13 is to limit the length or amount of toweling T that may be withdrawn from the case 10 at one operation and operates to stop turning of the member 12 after a predetermined amount of toweling has been withdrawn through the opening 30. When the member 12 is held against rotation by the means 13 the user is unable to pull or withdraw more toweling from the case. The means 13 includes a sprocket or ratchet wheel 37 attached to one end of the member 12 to turn therewith and a cam disc 38 arranged to turn with the member 12 and have limited rotative movement with respect thereto. Suitable plates 39 may be provided at the opposite ends or sides of the ratchet wheel 37 and the assembly of these plates and the wheel may be secured to the member 12 by screws 40. The projecting heads of the screws 40 are received in curving or arcuate slots 41 in the cam disc 38 which is positioned adjacent or against the outer plate 39. The means 14 includes a cam disc 42 which is preferably arranged adjacent the disc 38 and connected with the disc to simplify the construction. A plate 43 is interposed between the cam discs 38 and 42 and projects beyond their peripheries. The assembly of the cam discs 38 and 42 and the plate 43 may be welded or otherwise rigidly secured together. Spaced arcuate openings 44 are provided in the assembly of the discs 38 and 42 and the plate 43 to pass or receive pins 45. The pins 45 are shouldered to bear inwardly against the outer plate 39 and their reduced inner ends may be riveted to the inner

plate 39 and ratchet wheel 37 as at 46. The outer ends of the pins 45 are reduced to be riveted into openings 47 in a retaining plate 48. With the construction just described the connected cam discs 38 and 42 have limited rotative movement with respect to the control member 12 and are adapted to turn with the member 12 when this play or movement has been taken up.

The means 13 includes a lever 49 for cooperating with the cam disc 38. A pivot pin 50 is provided on an arm or bracket 51 to pivotally support the lever 49. The lever 49 is provided with an elongated opening or slot 52 receiving the pin 50 whereby it may pivot about the pin and have limited endwise movement. The lever 49 is in the same plane as the cam disc 38 and has an upwardly and forwardly projecting arm 53 provided with a finger 54 for cooperating with the cam disc. The periphery of the cam disc 38 has an inwardly curved portion terminating at an abrupt shoulder 55. The shoulder 55 faces in the direction the member 12 is turned when toweling is withdrawn from the case and is engageable by the finger 54. The engagement of the finger 54 with the shoulder 55 operates to prevent rotation of the member 12 in the direction indicated by the arrow X and thus prevents withdrawal of the toweling T from the case 10.

Means is provided for releasing the lever finger 54 from the shoulder 55. This means comprises a lower arm 56 on the lever 49 and a pawl 57 pivotally supported by the arm 56. The lower portion of the lever arm 56 may be U-shaped and may carry a pin 58 for pivotally supporting the pawl 57. The arm 56 projects downwardly and forwardly from the pivotal axis of the lever 49 so that the combined weight of the arm 56 and pawl 57 tends to move the lever downwardly on the pin 50 and normally tends to maintain the finger 54 in cooperation with the shoulder 55. The pawl 57 projects forwardly and has a finger or head 59 on its forward end for cooperating with the teeth 60 of the ratchet wheel 37. The head 59 and the teeth 60 are shaped and related to remain in cooperation and cause the pawl 57 to be drawn forwardly when the member 12 is turned in the direction indicated by the arrow Y and to ratchet or release when the member 12 is turned in the opposite direction indicated by the arrow X. The pawl 57 has a rearwardly projecting arm 61 which is of greater weight than its forward arm to normally urge the head 59 upwardly into cooperation with the ratchet teeth 60. The assembly of the lever 49 and the pawl 57 constitutes an escapement operating with the ratchet wheel 37 and the cam disc 38 connected with the control member 12.

To release the means 13 the user pushes upwardly and inwardly on the portion of toweling T exposed through the opening 36 to turn the member 12 in the direction indicated by the arrow Y. This turning of the member 12 in the direction indicated by the arrow Y of course results in turning of the ratchet wheel 37 so that the pawl 57 is moved forwardly to cause pivoting of the lever 49 and release of the head 54 from the shoulder 55. During this releasing movement of the member 12 the assembly of the cam discs 38 and 42 may remain stationary due to the provision of the slot and pin connections 44—55. The relative movement between the ratchet wheel 37 and the cam disc 38 is sufficient to allow the disengagement of the head 54 from the shoulder 55. Upon the disengagement of the head 54 from the shoulder 55 the weight of the

pawl 57 and the lower lever arm 56 moves the lever 49 downwardly on the pin 50 until the upper end of the slot 52 engages the pin. This downward movement of the lever 49 brings the head 54 to a position where it is prevented from re-engaging the shoulder 55 until the member 12 has been rotated one complete revolution in the direction indicated by the arrow X. A boss 64 is provided on the lever arm 53 to cooperate with a stop 65 on the support 28 to limit the outward or rearward movement of the lever arm.

The means 14 operates to prevent the withdrawal of unlimited quantities of toweling T from the case 10 by pulling downwardly and forwardly on the protruding toweling even though the means 13 may be released following the withdrawal of one portion or length of toweling. The means 14 is governed or released by the cutting free of the withdrawn portion of toweling T and includes a gate element or apron 66 engageable by the toweling T extending through the opening 30. The apron 66 is disposed within the case 10 above the opening 30 and is inclined upwardly and forwardly to be engageable by the toweling T passing from the periphery of the member 12 to the opening 30. The apron 66 is supported or suspended for swinging movement by plates 67 pivoted on the trunnions 29. One or both of the plates 67 has its greatest mass in front of its pivotal axis to normally urge the apron 66 rearwardly against the toweling T. The plate 67 adjacent the assembly of the cam discs 38 and 42 may have a notch 68 in its edge whose opposite end walls are adapted to engage the opposite ends of a stop 69 to limit the movement of the apron 66.

The means 14 includes a lever 70 pivotally supported by the pin 50 and adapted to cooperate with the cam disc 42 and plate 67. The lever 70 has a head or projection 71 on its forward end for cooperating with a notch 72 in the periphery of the cam disc 42. The notch 72 has an inclined wall 73 for cooperating with a correspondingly inclined surface of the projection 71. When the member 12 is turned in the direction indicated by the arrow Y to release the means 13 as described above, the projection 71 remains in cooperation with the notch 72. Following the release of the means 13 the user may push downwardly and inwardly on the toweling T trained over the member 12 to turn the member in the direction indicated by the arrow X to start or initiate the delivery of the toweling T through the opening 30. The turning of the member 12 in the direction indicated by the arrow X brings the wall 73 of the notch 72 into camming engagement with the head 71 to move the head out of the notch. As the rotation of the member 12 is continued either by pulling downwardly on the projected portion of toweling T or by turning the member through the medium of the toweling exposed through the opening 36, the projection 71 engages or rides on the periphery of the cam disc 42. The lever 70 has a rearwardly projecting arm 74 of greater weight than the forward arm of the lever to maintain the projection 71 in cooperation with the cam disc 42 through the action of gravity.

In accordance with the invention the lever 70 has cooperation with the adjacent plate 67 to prevent the cutting of the toweling T by the teeth 35 while the toweling is being withdrawn from the case. A lower projection 75 is provided on the outer end of the lever 70 to cooperate with a lateral lug 76 on the adja-

cent plate 67. When the projection 71 is moved downwardly out of the notch 72 as described above, the projection 75 is moved downwardly in front of the lug 76 to the position illustrated in Fig. 6 of the drawings. When the lever 70 is in this position its projection 75 cooperates with the lug 76 to prevent forward swinging or movement of the apron 66 and holds the apron in a position where the toweling T is prevented from engaging the teeth 35 as the user pulls the toweling downwardly through the opening 30. After the user has pushed downwardly and rearwardly on the toweling exposed at the opening 36 to turn the member 12 and release the means 13 he may grasp the portion of toweling T thus projected through the opening 30 and pull downwardly and forwardly on the toweling. This withdrawal of the toweling T causes the member 12 to be turned in the direction indicated by the arrow X. The toweling may be freely withdrawn through the opening 30 until the member 12 has been turned for one complete revolution, whereupon the shoulder 55 engages the head 54 to limit further rotation of the member.

Substantially simultaneously with the reengagement of the shoulder 55 with the head 54 the projection 71 re-enters the notch 72 releasing the apron 66 for forward movement. The user may then pull forwardly on the depending portion of toweling T to bring it against the teeth 35 and cut it free for use. The apron 66 freely swings forwardly during this cutting of the toweling T. The projection 75 and the lug 76 are related to prevent a second revolution of the member 12 in the event that the user attempts to obtain additional toweling by merely releasing the means 13 and pulling downwardly and forwardly on the withdrawn toweling without tearing free the withdrawn toweling T. When the projection 71 re-enters the notch 72 upon the member 12 being turned one revolution the lower edge 78 of the projection 75 is directly above and immediately adjacent the upper edge of the lug 76 (see Fig. 9). As long as the user maintains a forward pull on the withdrawn portion of toweling T without attempting to cut it free the upper edge of the lug 76 is disposed below the projection 75 so that the projection 71 is held in the notch 72 to prevent rotation of the member 12. While the member 12 is held against rotation by the cooperation of the projection 71 with the notch 72 the user is prevented from withdrawing toweling from the case 10.

It is believed that the operation of the towel cabinet will be readily understood from the foregoing detailed description. To operate the device the user pushes upwardly and inwardly on the toweling T exposed by the opening 36 to turn the member 12 in the direction indicated by the arrow Y. This partial rotation of the member 12 moves the pawl 57 forwardly so that the head 54 is swung out of engagement with the shoulder 55. The assembly of the cam discs 38 and 42 is free to remain stationary during the turning of the member 12 to release the head 54 from the shoulder 55. After the disengagement of the head 54 from the shoulder 55 the lever 49 shifts downwardly on the pin 50 so that the head is prevented from re-engaging the shoulder. Following the release of the means 13 the user pushes downwardly and rearwardly on the toweling T trained over the face of the member 12, whereupon the cam wall 73 of the

notch 72 cooperates with the projection 71 to shift the projection downwardly out of the notch. The turning of the member 12 also feeds a portion of the toweling T through the opening 30 5 which the user may grasp and pull downwardly and forwardly. The downward movement of the projection 71 out of the notch 72 brings the lever 70 to a position where its projection 75 is in front of the lug 76. The projection 75 10 cooperates with the lug 76 to hold the apron 66 in the position illustrated in Fig. 6 of the drawings. When in this position the apron 66 prevents the toweling T from engaging the teeth 35 as the user pulls the toweling through the opening 30. The user may freely withdraw the toweling T until the member 12 has been turned for one complete revolution to bring the shoulder 55 15 into engagement with the head 54. At this time the member 12 is moving in the direction 20 indicated by the arrow X and the shoulder 55 cooperating with the head 54 moves the lever 49 upwardly to bring the lower end of the slot 52 into engagement with the pin 50. This engagement prevents further turning of the member 12 and stops the withdrawal of the toweling. Substantially simultaneously with the engagement of the lower end of the slot 52 with the pin 50 the gravity actuated lever 70 moves to the position where its projection 71 is received 30 in the notch 72. This movement of the lever 70 disengages the rear edge of the projection 75 from the lug 76 freeing the apron 66 for forward movement.

In practice the user usually maintains a downward and forward pull on the toweling as he withdraws it and the sudden release of the projection 75 from the lug 76 allows the apron 66 to suddenly move forwardly to bring the toweling T against the teeth 35. In this manner the toweling T is readily cut free for use. In the event that the user does not cut the toweling free and attempts to obtain further toweling by merely releasing the means 13 and maintaining a downward and forward strain on the toweling the lug 45 76 remains directly below the projection 75 to prevent the disengagement of the projection 71 from the notch 72. The projection 71 thus prevents turning of the member 12 and withdrawal of toweling, see Fig. 9.

50 The supply roll 11 of toweling is supported by the control member 12 and is urged to turn in a direction to permit the free reeling of the toweling from it. As the supply roll 11 is supported on the member 12 no other means is required for carrying the supply of toweling. When the supply roll 11 of toweling becomes reduced in diameter it may be partially supported by the support 28. The control member 12 engages the toweling T to govern its withdrawal from the case 10 and constitutes a backing for the portion of toweling T that is engaged or manipulated by the user. Further, the control member 12 constitutes the manually actuated element of the device but is housed by the case 10 and toweling 65 T so that the user does not directly contact it. The portion of toweling T exposed at the opening 36 is engaged by the user to release and actuate the control mechanism and this self-same portion of toweling is later withdrawn for use 70 by the same person. The device may be fully actuated and controlled without the direct manual engagement of any parts of the mechanism. The series of acts or manipulations required for the operation of the device is such that the user 75 is usually deterred from withdrawing excessive

quantities of toweling. The control member 12 operates as a measuring element and provides for the withdrawal of a predetermined length of toweling T at each operation. The parts of the control mechanism are entirely automatic in operation and are gravity controlled and do not require springs for their operation. The case 10 is particularly simple and inexpensive of manufacture and the front section B may be swung to its open position to make the interior of the case readily accessible. The supply roll of toweling may be easily positioned in the case without being arranged on a shaft or rod.

Having described only a typical preferred form and application of my invention, I do not wish to be limited or restricted to the specific form and application herein set forth, but wish to reserve to myself any modifications or variations that may appear to those skilled in the art or fall within the scope of the following claims.

Having described my invention, I claim:

1. A device for handling sheet material including a case for holding a supply of the material, the case having an opening through which a portion of the material confined within the case against use is engageable by the operator, a control member in the case having movement controlling engagement with the material and positioned with respect to the opening to be movable by manual force applied to said portion of material accessible through the opening, a cutting part adapted to cut free the material withdrawn from the case, and means for preventing movement of the member released by the cutting free of the said material.

2. A device for handling sheet material including a case for holding a supply of the material, the case having an opening through which the material may be removed from the case and having a second opening, a member having movement controlling engagement with the material and movable by manual action on the material accessible through the second opening, a control for stopping movement of the member to limit the removal of the material releasable by such manual action on the material accessible through said second opening and means for cutting free the portions of material removed through the first opening.

3. A device for handling sheet material including a case for holding a supply of the material, the case having an opening through which the material may be removed from the case and having a second opening, a control limiting the removal of material from the case including a member movable by manual action on the material accessible through the second opening, means for cutting free the portions of material removed through the first opening, and means actuated by the member for controlling the cutting means.

4. A device for handling sheet material including a case for holding a supply of the material, and a control for governing the removal of material from the case including a member having movement controlling engagement with the material, manually releasable means for stopping movement of the member when a definite portion of the material has been removed from the case, and means preventing further material removing movement of the member following the release of said means made operative by a forward pull on the removed portion of the material.

5. A device for handling sheet material including a case for holding a supply of the material, and a control for governing the removal of ma-

- terial from the case including a member mounted to be manually movable through the medium of the material and having movement controlling engagement with the material, manually releasable means for stopping movement of the member when a definite portion of the material has been removed from the case, a cutting part against which the material may be moved to cut free the removed portion of material, and means preventing material removing movement of the member made operative by a pull on the removed portion of the material and released on cutting free the said portion of the material.
6. A device for handling sheet material including a case for holding a supply of the material, and a control for governing the removal of material from the case including a member having movement controlling engagement with the material, manually releasable means for stopping movement of the member when a definite portion of the material has been removed from the case, and means preventing material removing movement of the member made operative by a forward pull on the removed portion of the material, the last mentioned means including a part for engaging the material where it leaves the case.
7. A towel cabinet including a case for holding a supply of toweling and a control governing the withdrawal of toweling from the case including a manually movable member having movement controlling engagement with the toweling, a shouldered part having a lost motion connection with the member, a lever adapted to cooperate with the shoulder of said part to stop movement of the member, and means for releasing the lever including teeth on the member, and a pawl connected with the lever and adapted to cooperate with the teeth to transmit releasing motion from the member to the lever.
8. A towel cabinet including, a case adapted to house a supply roll of toweling and having an opening through which the toweling may be withdrawn and having a second opening, a rotatable member in the case in feeding relation to the supply and adapted to have a portion of toweling trained over it to be engageable through said second opening for the purpose of turning the member, a cutting element adapted to cut free a withdrawn portion of toweling, and a control governing rotation of the member.
9. A towel cabinet including, a case having an opening and adapted to house a supply roll of toweling, a rotatable member in the case in feeding relation to the supply roll and adapted to have a portion of toweling trained over it to be engageable through said opening for the purpose of turning the member, a cutting element adapted to cut free a withdrawn portion of toweling, and a control governing rotation of the member and for governing engagement of the toweling with the cutting element.
10. A towel cabinet including a case having an opening and adapted to house a supply roll of toweling, a rotatable member in the case in feeding relation to the supply roll and adapted to have a portion of toweling trained over it to be engageable through said opening for the purpose of turning the member, a cutting element adapted to cut free a withdrawn portion of toweling, and a control governing rotation of the member, the control including a ratchet wheel rotatable with the member and an escapement mechanism for cooperating with the ratchet wheel.

11. A towel cabinet including, a case having an opening and adapted to house a supply roll of toweling, a rotatable member in the case in feeding relation to the supply roll and adapted to have a portion of toweling trained over it to be engageable through said opening for the purpose of turning the member, a cutting element adapted to cut free a withdrawn portion of toweling, a control for limiting rotation of the member releasable by manipulation of the member through the medium of said portion of the toweling, and means coating with the control for governing the operation of the cutting element.

12. A device of the character described including a case for holding a supply of sheet material, the case having an opening through which the material may be withdrawn and a second opening past which the material is movable to the first opening, a member in the case behind the material passing the second opening, the member being rotated by movement of the material, means limiting rotation of the member to limit the withdrawal of the material, means at the first opening for cutting the withdrawn material free, and means preventing engagement of the material with the cutting means releasable substantially simultaneously with the operation of the first mentioned means.

13. A device of the character described including a case for holding a supply of sheet material, the case having an opening through which the material may be withdrawn and a second opening past which the material is movable to the first opening, a member in the case behind the material passing the second opening, the member being rotated by movement of the material, means limiting rotation of the member to limit the withdrawal of the material, means at the first opening for cutting the withdrawn material free, and means preventing engagement of the material with the cutting means releasable substantially simultaneously with the operation of the first mentioned means, the last mentioned means including an element for engaging the material, a part rotatable with the member and having a notch, and a pivoted lever engaging the element and cooperating with the said part to be maintained in holding engagement with the element by said part and releasable from the element upon moving into said notch.

14. A device of the character described including a case for holding a supply of sheet material, the case having an opening through which the material may be withdrawn and a second opening past which the material is movable to the first opening, a member in the case behind the material passing the second opening, the member being rotated by movement of the material, a cutting part at the first opening for cutting free the withdrawn portion of toweling, and means preventing engagement of the material with the cutting part releasable after a predetermined rotation of the member.

15. A device of the character described including a case for holding a supply of sheet material, the case having an opening through which the material may be withdrawn and a second opening past which the material is movable to the first opening, a rotatable member in the case engaging the material passing the second opening to control its movement, means operable to stop rotation of the member after the withdrawal of a predetermined amount of material and releasable by reverse rotation of the member, means for cutting free the withdrawn material, and

means for preventing rotation of the member in the event the first mentioned means is released and an attempt is made to withdraw more material without cutting the withdrawn material free.

5 16. A device for dispensing paper toweling including a case for housing a supply of toweling, the case having an opening through which the toweling may be withdrawn, a cutting part against which the toweling may be brought to cut free the toweling withdrawn from the opening, releasable means for preventing engagement of the toweling with the cutting part, a control operable to stop the withdrawal of the toweling, and means for releasing said releasable means substantially simultaneously with the operation of the control.

10 17. A device for dispensing paper toweling including a case for housing a supply of toweling, the case having an opening through which the toweling may be withdrawn, a cutting part against which the toweling may be brought to cut free the toweling withdrawn from the opening, releasable means for preventing engagement of the toweling with the cutting part, manually 15 releasable means for automatically limiting the withdrawal of the toweling, means for releasing the first mentioned means, and means for preventing the subsequent withdrawal of the toweling released by the act of bringing the toweling 20 into engagement with the cutting part.

25 18. A device for dispensing paper toweling including a case for housing a supply of toweling, the case having an opening through which the toweling may be withdrawn, and a second opening, a control including a movable member in the case having movement controlling engagement with the toweling which is trained over it to be accessible through the second opening, releasable means for stopping movement of the member to limit withdrawal of the toweling, means operable by a pull on the withdrawn por-

tion of the toweling to cut the same free, means operable by manual action on the member through the medium of the toweling accessible through the second opening for releasing the releasable means, and means for preventing toweling withdrawing movement of the member releasable by said pull on the withdrawn portion of the toweling.

5 19. A device for dispensing paper toweling including a case for holding a supply of the toweling and having an opening through which the toweling may be withdrawn and having a second opening, a movable member having movement controlling engagement with the toweling, the material engaging the member being accessible 10 through the second opening, means for limiting forward movement of the member released by rearward movement of the member transmitted thereto by manual action on the toweling accessible through the second opening, a cutting 15 part against which the toweling may be engaged to free the toweling withdrawn from the case, and means for preventing engagement of the toweling with the cutting part released substantially simultaneously with the actuation of the 20 first mentioned means.

25 20. A towel cabinet comprising, a case for holding a supply of toweling, the case having a towel dispensing opening and a second opening through which a portion of the toweling confined within the case is engageable by the operator, a dispensing member in the case having engagement with the toweling and positioned relative to the said second opening to be movable by manual force applied to said portion of the toweling, a cutting 30 part operable to cut free the toweling dispensed through the dispensing opening, and means for holding the dispensing member against movement released by such cutting free of the dispensed toweling.

35 40 LEO M. HARVEY.
